United States Patent Office

Des. 193,658
Patented Sept. 25, 1962

193,658

ACOUSTICAL TILE

Sharon de Leon, Chicago, Ill., assignor to The Celotex Corporation, Chicago, Ill., a corporation of Delaware

Filed Sept. 5, 1961, Ser. No. 66,608

Term of patent 14 years

(Cl. D18—2)

Fig. 1.

Fig. 2.

FIGURE 1 is a front face view of an acoustical tile showing my new design; and

FIGURE 2 is a cross-sectional view taken along lines 2—2 of FIGURE 1 of said acoustical tile.

I claim:

The ornamental design for an acoustical tile, as shown.
